SIDE FRAME AND BRAKE SUPPORT
STRUCTURE

Claus J. Werner Clasen, Chicago, Ill., assignor to
American Steel Foundries, Chicago, Ill., a corporation of New Jersey

Application July 17, 1947, Serial No. 761,598

6 Claims. (Cl. 188—205)

1

My invention relates to railway car trucks and has particular reference to novel support means for the truck brake rigging.

The principal object of the invention is to provide a bracket which is cast integral with the side frame and which will serve as a support for several parts of the brake mechanism of the truck.

A further object of the invention is to design a bracket of the type described possessing the characteristics of light weight, necessary strength and simplicity of design, and economy of manufacture.

A still further object of the invention is to devise a novel support for a structure carrying a portion of the brake mechanism.

These and other objects of the invention will be apparent from the specification and drawings, wherein:

Figure 1 is a fragmentary side elevation of a truck structure incorporating my novel invention;

Figure 2 is a horizontal sectional view taken substantially in the plane indicated by line 2—2 of Figure 1 showing the bolster as associated with the side frame; and

Figure 3 is a sectional view taken in the plane substantially as indicated by line 3—3 of Figure 1.

Referring to the drawings in detail, the invention is illustrated in connection with a railway car truck comprising the side frame 2 (Figure 1) having a compression member 4, a tension member 5, and an integral upright column 6 adjacent each end of the frame and merging with said compression and tension members and defining therewith a bolster opening 8 (Figure 1) centrally of the side frame and a window opening 10 adjacent each end of the frame.

A bolster 12 (Figure 2) may have an end disposed in the bolster opening 8, the bolster being spring-supported from the side frame in the usual manner, as will be readily understood by those skilled in the art. The bolster may be provided at each side thereof with inboard and outboard interlocking gibs or lugs 14 and 16 embracing the adjacent column therebetween.

Each column 6 may be of U section comprising inboard and outboard webs or walls 18 and 20 joined by an intermediate wall or web 22.

On the inboard side of the frame at the juncture between each column and the compression member is formed an integral bracket 28, (Figures 1 and 3) the bracket comprising a vertically disposed laterally extending substantially rectangular web 30 integrally formed with the inboard side of the compression member and the adjacent

2

inboard column member wall 18, the web 30 being offset as at 31 (Figure 2) adjacent the column to afford clearance for the associated inboard bolster lug 14.

At the upper corner of the web 30 remote from the frame is formed a jawlike structure, generally designated 32, comprising a pair of diagonally arranged vertically spaced substantially parallel webs or flanges 34, 34 extending from one side of said web 30 in a direction toward the adjacent end of the frame and forming a throat 36 adapted to seat the top chord of a loop hanger (not shown) in the usual manner.

The flanges 34, 34 are provided with vertical openings 38, 38 for reception of a pin (not shown) for securing the associated loop hanger, as will be readily understood by those skilled in the art.

The upper flange 34 is connected to the compression member of the side frame by a laterally extending arcuate web 40 merging at opposite ends with the inboard side of the compression member and said upper flange 34. A vertical rib 41 joins the top surface of the upper flange 34 and the top surface of the web 40. The web 40 also merges at the edge adjacent the bolster opening, with the top edge of the web 30, thus strengthening the connection between the web 30 and the side frame. To lighten the structure the web 30 may be cored away as at 42 (Figure 3).

On the web 30 beneath said bolster structure 32 is mounted a bracket 44 affording support for a tubular member, support or crosspiece 46 extending between the side frames of the truck and constituting a basal contact member for engagement with and actuation of a load compensating device forming part of the brake mechanism. The load compensating device is not shown inasmuch as it forms no part of the present invention. Suffice it to say that the crosspiece 46 serves as an actuating part for said load compensating device.

The bracket 44 comprises a vertical web or mounting plate 48 seated against the web 30 of the bracket 28 beneath said structure 32. At one end of the web 48 is formed a cylindrical housing 50 closed at the end adjacent the web 48 by a wall 52, the wall 52 merging with said web 48. Within the housing are disposed a pair of axially spaced cylindrical resilient bushings 54, 54 such as rubber, said bushings being sleeved over the adjacent end of the crosspiece 46 and affording a resilient support therefor. It will be noted that the cylindrical housing is formed at its open end with a pair of axially spaced inturned annular flanges 55, 55, the flanges being spaced from the end of the tubular member 46 whereby said tu-

ular member is afforded universal angling with respect to the bracket 44 against the compression of the resilient bushings 54.

Horizontally disposed reinforcing gussets 56, 56 connect the wall 52 of the cylindrical housing 50 with the opposite sides of the web 48 of the bracket 44.

The brackets 28 and 44 are connected to each other by a plurality of bolts 58, 58 extending through aligned openings in the webs 30 and 48 of the respective bracket.

To reduce the stresses on the bolts, the web 30 of the bracket 28 is provided with a horizontal ledge or flange 60 at the bottom edge thereof, said ledge extending laterally from one side of the web 30 beneath the structure 32 and affording a seat as at 62 for the lower edge of the web 48 of the bracket 44. At the juncture between the web 30 and the ledge 60, the web 30 may be cored away as at 64 (Figures 2 and 3) to insure a close fit for the web 48 of the bracket 44. For the same purpose the web 48 of the bracket 44 is provided on the surface facing the web 30 with a vertical flange 66 which seats against the vertical edge of the web 30 as at 68. The flange 66 on the side opposite that which seats against the web 30 is connected to the adjacent gusset 56.

It is to be understood that I do not wish to be limited by the exact embodiment of the device shown which is merely by way of illustration and not limitation as various and other forms of the device will, of course, be apparent to those skilled in the art without departing from the spirit of the invention or the scope of the claims.

I claim:

1. In a railway car truck, a side frame comprising a compression member and an upright column connected thereto, said column being of U section and comprising inboard and outboard walls and an intermediate wall connecting said inboard and outboard walls, a bracket on the inboard side of said frame integrally formed on said inboard wall of said column and the inboard side of said compression member and comprising a substantially vertical rectangular web extending laterally of said frame, a jawlike structure formed on the upper portion of said web and comprising spaced hanger-suspending elements, a web connecting one of said elements with said compression member and merging with the top edge of said first-mentioned web, said first-mentioned web being formed and arranged to afford support and connection for an associated brake part beneath said jawlike structure.

2. In a railway car truck, a side frame comprising, a compression member and an upright column connected thereto, brake support means at the inboard side of said frame including a brake hanger support structure connected to said member and column, a substantially vertical wall beneath said structure extending transversely of the frame and connected at its upper edge to said structure and at its outboard edge to said column, a bracket comprising a vertical web disposed beneath said structure and seated against the adjacent side of said web and removably connected thereto, a beam disposed in alignment with said web and wall transversely of said truck, an element connected to said web and sleeved over an end of said beam, and resilient means compressed between said element and said beam end.

3. In a railway car truck, a side frame comprising a compression member and an upright column connected thereto, a brake hanger support

structure connected to the inboard side of said column and member, a substantially vertical wall beneath said structure connected thereto and to said column, a bracket having a web seated against said wall beneath said structure, a sleeve adjacent the inboard edge of said wall in alignment therewith transversely of said frame and connected to said web, means on said web affording a seat therefor against said inboard edge of said wall, means on said wall beneath said web affording a seat therefor, a brake member extending transversely of the truck and having an end received within said sleeve, and resilient means compressed between said sleeve and said end.

4. In a railway car truck, a side frame having a column and a compression member, a brake hanger support structure connected to said column and member, a generally vertical wall beneath said structure extending transversely of the frame and connected at its upper edge to said structure and at its outboard edge to said column, a bracket having a web removably connected to said wall, a sleeve integral with said web disposed inboardly of said wall in alignment therewith transversely of said frame, a beam extending into said sleeve, and resilient means compressed between said beam and sleeve to afford a resilient connection therebetween, said resilient means and said beam being formed and arranged to permit disconnecting the same by sliding said beam out of said resilient means.

5. In a truck, a side frame including a compression member and an upright column connected thereto, a bolster having spaced inboard and outboard lugs receiving said column therebetween, a substantially vertical wall connected to the inboard side of said column and extending transversely of the frame and being offset around said inboard lug toward said bolster, a brake hanger supporting structure connected to the upper edge of said wall and to the inboard side of said compression member and column and extending away from said bolster, a bracket having a web seated against said wall on a side thereof remote from said bolster, means extending through said web and said wall removably connecting the same, a beam support element disposed inboardly of said wall in overlapping relationship with respect thereto and connected to said web, a beam extending transversely of said frame in alignment with said wall and web and projecting into said element, and resilient means under compression between said element and said beam.

6. In a railway car truck, a side frame, a bolster having spaced inboard and outboard lugs embracing a portion of said frame therebetween, brake support means including a brake hanger support structure connected to the inboard side of said frame adjacent said bolster and having spaced jaw members extending in a direction away from the bolster, a substantially vertical wall extending laterally of said frame and connected at one of its vertical edges to said structure and at one of its lateral edges to the inboard side of the frame, said wall being offset at said one lateral edge inboardly of said inboard lug toward said bolster, a brake frame support bracket comprising a mounting web seated against a side of said wall remote from said bolster and removably connected thereto, an integral sleeve on said web disposed inboardly of said wall and having one side thereof extending from said web toward the bolster and overlapping said wall, a beam ex-

tending transversely of said truck and having an end fitted into said sleeve, and resilient bushings sleeved onto said end and compressed between said sleeve and said end.
